UNITED STATES PATENT OFFICE.

HUGO A. J. THIESEN, OF ST. LOUIS, MISSOURI.

CURRENT-MOTOR.

1,365,871.

Specification of Letters Patent. Patented Jan. 18, 1931.

Application filed April 5, 1920. Serial No. 371,535.

To all whom it may concern:

Be it known that I, HUGO A. J. THIESEN, a citizen of the German Republic, residing at St. Louis, State of Missouri, have invented 5 certain new and useful Improvements in Current-Motors, of which the following is a full, clear, and exact description, reference being had to the accompanying drawings, forming a part hereof.

10 The present invention is directed to improvements in current motors, and particularly to water wheels disposed in the path of a stream of water, although the application of currents of air or gases is not to be excluded. The object of the invention is to utilize one or more pairs of wheels mounted on a common shaft, the wheels of any pair rotating simultaneously in opposite directions, the corresponding wheels of any pair 15 (where more than one pair are employed) rotating in the same direction. By this arrangement a maximum efficiency is developed from a given current, the construction of the motor is simplified, and its installation rendered easy, all as will more 20 fully appear from the following detailed description of the invention in connection with the accompanying drawings in which—

Figure 1 represents a side elevation of a 25 portion of a frame in which the water wheels are mounted, parts being shown in section; Fig. 2 is a front elevation of Fig. 1; Fig. 3 is a top plan of the wheels shown in Fig. 1, the outer casing being in section; Fig. 4 is a vertical cross-section through the 30 wheel shaft taken on the line 4—4 of Fig. 5 between the gear hubs of two adjacent wheels; Fig. 5 is a sectional detail through the gear hubs of two adjacent wheels along a 35 radial plane through the axis of the wheel shaft; Fig. 6 is a front elevation of a frame showing four independent sets of wheels; and Fig. 7 is a vertical sectional detail showing the bottom apron leading to the wheel 40 casing.

Referring to the drawings, 1, represents 45 suitable cylindrical casings held in rigid position by a frame F composed of structural members 2, here shown as I-beams, the frame being built to hold any desired number 50 of casings depending on the horse power to be developed. At the bottom of the frame in the rear, or on the side facing the current are hinged aprons 3 which serve to direct 55 the current to the bottom casings and pre-

vent the current from undermining the structure by eddying and washing away the sands. Disposed in the casing 1 at each end thereof (all the casings being alike so that a description of one will suffice for all) is a 60 spider provided with a central hub 4 and radiating arms 5, the outer ends of the latter being made fast to the inner wall of the casing by angle pieces 6 as shown (Fig. 2). The hubs 4 of the spiders are disposed along 65 the axis of the casing 1 and form bearings for the ends of the wheel shaft S, the front projecting end of the shaft terminating in a bevel gear wheel 7. Mounted loosely on the shaft S at the center thereof is the hub 8 70 of the water wheel W, and keyed to the shaft on either side of the loose wheel W are the hubs 9 and 10 of the fast wheels W', W'', respectively. The wheels W, W', constitute members of a pair in which provision is 75 made to cause the loose wheel W to rotate in one direction while the fast wheel W' and its shaft S rotate in the opposite direction in direct response to the current. This provision is as follows: The inner adjacent ends 80 of the hubs 8, 9, are formed with bevel gears or gear rings 11, 11, which mesh with bevel pinions 12 loosely mounted on studs or spindles 13 extending in diametrically opposite directions from a sleeve 14 mounted 85 loosely on the shaft S between the hubs. It is apparent from the connections described that when the wheel W' keyed to the shaft rotates in one direction, it will impart simultaneous rotation to the loose wheel W in the 90 opposite direction. This reverse direction is assisted by the waters discharged from the wheel W', the current impinging against the blades of the wheel W' so as to turn it and the shaft S in one direction, while the waters 95 leaving said wheel impinge against the blades of the loose wheel W so as to impart thereto a rotation in the opposite direction, it being understood that the blades of the two wheels are not only transversely curved 100 in opposite directions but are set at an angle to the planes of rotation of the wheels, those on one wheel being set reversely to the blades of the adjacent wheel. This causes the current to drive one wheel (W') in one direction, the discharge waters therefrom impinging against the blades of the adjacent wheel (W) so as to drive it or tend to drive it in the opposite direction, this opposite 105 direction being rendered fully responsive to 110

the current by the gearing interposed between the wheels as previously described. The wheel W'' is fast on the shaft S , the same as the wheel W' , the blades of the 5 wheel W'' being set and curved to correspond with the blades of the first wheel (W') so that when the waters discharged from the loose wheel W impinge against the 10 blades of the last wheel (W'') they will drive or tend to drive said wheel and the shaft S in the same direction as the wheel W' . Thus, with the foregoing arrangement the maximum efficiency results from the action of the current, the latter driving the 15 wheels exposed thereto with full force and effect and consequently driving the shaft S from which the power is taken and distributed to other machinery. In the present embodiment of the invention the bevel gear 20 wheel 7 terminating the front end of the wheel shaft meshes with a horizontal bevel gear 15 on a vertical shaft 16, the latter terminating at the top in a bevel gear 17 which in turn engages a vertical gear 18 on the main transmission shaft 19 from which the power may be conducted to any suitable 25 point of consumption not shown. The casings 1 are secured to the upright structural members of the frame F by means of plates 30 secured to the outer walls of the casings, said plates being provided with claws or hooks d which engage the flanges of the I-beams constituting such structural members. Any equivalent means for anchoring the 35 casings to the frame fall within the scope of my invention.

In Fig. 6 are shown a battery of four motors, there being two vertical shafts 16 each driven by a pair of motors, and each 40 shaft contributing its share in driving the shaft 19. The operation is obvious from Figs. 1 and 3, it being clear that as rotation is imparted to the wheels W' , W'' , the shaft S will be rotated, and from said shaft the 45 motion is transmitted to the other shafts, the gear connections between the middle loose wheel W , and the first wheel W' of the series keyed to the shaft, making certain that the speed of reverse rotation of said loose wheel 50 is fully commensurate with the speed of rotation of the wheel W' , so that the waters discharged from said loose wheel will in turn act on the last wheel W'' to impart to it a rotation speed commensurate with that 55 of the wheel W' . Obviously, the details shown may be considerably altered without involving a departure from either the nature or spirit of the invention. Features shown but not alluded to are well understood in the 60 art and require no description in the present connection.

Having described my invention what I claim is:

1. A current motor of the character described, comprising a pair of wheels, a com-

mon supporting shaft therefor, one of the wheels being tight and the other loose on said shaft, means for causing rotation in a given direction to be imparted to the first wheel by the current traversing the wheels, 70 a power transmitting member mounted on the shaft between the wheels, and intermediate connections between said member and the wheels for imparting to the second or loose wheel a simultaneous rotation in the 75 opposite direction.

2. A current motor of the character described, comprising a pair of wheels, a common supporting shaft therefor, one of the wheels being tight, and the other loose on 80 said shaft and spaced from the first wheel, means for causing rotation in a given direction to be imparted to the first wheel by the current traversing the wheels, a sleeve mounted loosely on the shaft between the 85 wheels, pinions on the sleeve disposed at points diametrically opposite one another and rotating loosely on the sleeve about axes disposed at right angles to the axis of the shaft, and gear rings on the adjacent 90 faces of the wheels meshing with said pinions whereby simultaneous rotation in the opposite direction is imparted to the loose wheel.

3. A current motor of the character described, comprising a shaft, a wheel loosely mounted thereon, a wheel keyed or made tight to the shaft disposed on each side of the loose wheel, means for causing rotation in a given direction to be imparted to one of the tight wheels by the current traversing the wheels, intermediate connections between 95 said tight wheel and loose wheel for imparting to the latter a simultaneous rotation in the opposite direction, the second tight 105 wheel or that on the opposite side of the loose wheel receiving the discharges from the latter wheel, and suitable means on the second tight wheel actuated by said discharges, thereby supplementing the action 110 of the current on the first tight wheel.

4. A current motor of the character described, comprising a shaft, a radially bladed wheel loosely mounted thereon, a radially bladed wheel keyed or made tight to 115 the shaft disposed on each side of the loose wheel, the blades of the loose wheel being set at an angle to the plane of rotation of the wheel and at an angle to the direction of flow of the current, the blades of the tight 120 wheels being set at a similar angle to the rotation plane but reversely to the blades of the loose wheel, mechanical devices interposed between the tight wheel directly exposed to the current and the loose wheel for 125 imparting to the latter rotation in the opposite direction to that imparted to the tight wheel by the current traversing the wheels, the second tight wheel receiving and being actuated by the discharges from the loose 130

wheel, whereby the action of the current on the first tight wheel is supplemented by said discharges.

5. In a current motor of the character described, a shaft, a water wheel keyed thereto, a second wheel mounted loosely on the shaft and spaced from the tight wheel, gear rings on the adjacent faces of the wheels disposed about the axis of the shaft, a sleeve 10 mounted loosely on the shaft between the wheels, studs or spindles radiating from said sleeve, and pinions mounted loosely on the studs and meshing with the gear rings aforesaid.
- 15 6. In a current motor of the character described, a shaft, a bladed water wheel

mounted loosely thereon, bladed water wheels made tight to the shaft on opposite sides of the loose wheel, the loose wheel receiving the discharges from one of the tight 20 wheels and rotating in a direction opposite thereto and to the shaft, and the second tight wheel receiving the discharges from the loose wheel and turning with the shaft and first tight wheel.

In testimony whereof I affix my signature, in presence of two witnesses.

HUGO A. J. THIESEN.
